UNITED STATES PATENT OFFICE.

BENJAMIN F. BELLows, OF CLEVELAND, OHIO, ASSIGNOR TO JOHN WOODRUFF SIMPSON, OF NEW YORK, N. Y.

ELEVATOR MECHANISM FOR CIRCULATING-MATRIX MACHINES.

SPECIFICATION forming part of Letters Patent No. 784,133, dated March 7, 1905.

Application filed July 11, 1904. Serial No. 216,044.

To all whom it may concern:

Be it known that I, BENJAMIN F. BELLows, a citizen of the United States, residing at Cleveland, in the county of Cuyahoga and State of Ohio, have invented a certain new and useful Improvement in Elevator Mechanism for Circulating-Matrix Machines, of which the following is a full, clear, and exact description, reference being had to the accompanying drawings.

This invention is an improvement in machines for casting type-bars; and it relates to the mechanism whereby the lines of matrices are transferred from the casting mechanism to the distributing-rail of such a machine. In many of its essentials the mechanism constituting the present invention resembles the mechanism for the same purpose which is shown and described in my prior patent, No. 598,408.

The object of this invention is, generally speaking, to so modify and supplement that mechanism that it will be more durable and more efficient and certain in its operation.

In the drawings, Figure 1 is a front elevation of as much of a type-bar-making machine as is necessary to disclose the present invention and its relation to the other associated parts of said machine. Fig. 2 is an elevation from the left side of Fig. 1. Fig. 3 is a front view of the lower part of the mechanism in which the present invention is embodied. Fig. 4 is a sectional side view of the mechanism shown in Fig. 3 viewed in the direction of the arrow A. Fig. 5 is a front view of the upper part of the mechanism embodying the invention when the elevator is down. Fig. 6 is a sectional side view of the mechanism which is shown in Fig. 5 viewed in the direction indicated by arrow B. Fig. 5 is an upward continuation of Fig. 3, and Fig. 6 is an upward continuation of Fig. 4. Fig. 7 is a full-sized front elevation of the upper part of said mechanism when the elevator is in its highest position. Fig. 8 is a horizontal section on line C C of Fig. 7. Fig. 9 is a left side view of the mechanism shown in Fig. 7. Fig. 10 is a right side view of the same mechanism.

Extending up from the part of the machine on which the elevator rests when in its lowest position to a point above the distributing-rail 1 is a vertical post 2, which is embraced by the elevator 3, for which it serves as a guide. The elevator has on its rear side a matrix rail or shelf 4, onto which the matrices are placed when the elevator is in its lowest position, at which time said elevator rests upon a part of the machine-frame. The elevator is attached to the ends of a sprocket-chain 5, which runs under a sprocket-wheel 6, placed below the lowest position the elevator reaches, and over another sprocket-wheel, 7, mounted above the distributing-rail on a fixed part of the machine-frame. The upper sprocket always runs idly, but the lower sprocket is loose on a rotating shaft 8, to which it may be clutched whenever it is desired to lift the elevator.

Behind the upper part of the post 2 and parallel thereto is a bar 9, in which the rack-slide 10 is guided in a vertical path. Another horizontally-movable rack-slide, 12, is mounted in suitable guides behind the distributing-rail, and both of these rack-slides engage with a freely-rotatable pinion 13, whereby the upward or downward movement of slide 10 rotates the pinion 13, which thereby causes slide 12 to move, respectively, to the left or right. Secured to slide 12 is a push-bar 18, which extends forward into a plane a little above the distributing-rail.

It is the upward movement of the elevator which lifts slide 10, because the elevator carries a latch in the form of a hook-lever 14, which may project beneath a spring-pawl 11, pivoted to the front side of slide 10, near the lower end thereof. On the inner face of a flange 15, which projects rearward from the post 2, near its lower end, is a cam-groove 16, into which friction-roller 17, mounted on the lever 14, projects, whereby as the elevator goes down the lever is moved forward and the hook thereof is drawn into the elevator and is there held while the elevator is down. This grooved flange 15 only extends a short distance above the elevator when it is down. At a point near the lower end of the slide 10

this flange again appears, and on its inner face is the cam-groove 19, which engages with said roller 17 and pushes this latch-lever outward as the elevator goes up, so that the hook 5 thereon is moved beneath the spring-pawl 11 on slide 10. Thereafter as the elevator continues its upward movement it carries the slide 10 up with it until the slide has moved up so far that the accompanying movement of slide 12 has carried the push-bar 18 over to the left of the path of the elevator. Then the cam-groove 19 on flange 15 withdraws the latch-lever and frees the slide. At that time, however, the slide 10 has reached a point 15 where a spring-pawl 20, mounted on the bar 9, enters a notch 21 in the rear side of the slide 10 and prevents the slide from dropping. This spring-pawl is attached to a rock-shaft 22, having an arm 23, which projects into the 20 path of a pin 24 on the side of the elevator.

After the slide 10 has been released by the elevator and is being upheld by the pawl 20 the elevator continues its upward movement until its rail 4 is just a trifle above the distributing-rail 1. At that instant the lower sprocket 6 is disconnected from its shaft through the operation of mechanism to be described presently. Then the elevator settles back onto a spring-pawl 25, pivoted to bar 9 30 and projecting into a notch 26 in the rear side of the elevator, the rail of the elevator being then in line with the distributing-rail. Just as the elevator reaches its highest point the pin 24 thereon strikes the arm 23 and moves 35 it, thereby withdrawing the pawl 20 from its engagement with the notch 21 in slide 10. This slide being thus released falls, thereby turning the pinion 13, whereby the slide 12 is moved to the right. The push-bar 18 there- 40 on sweeps the matrices from the elevator onto the distributing-rail. Just after this has been accomplished a cam 27 on the descending slide 10 strikes the tail of the spring-pawl 25 and withdraws said pawl from the notch 26 in the 45 elevator, whereupon the elevator falls by gravity to its rest position. During the downward movement of the elevator the hook-lever 14 will strike the spring-pawl 11; but because said pawl is movable it is pushed 50 aside by the hook-lever; but the spring returns the said pawl to its normal position in the path of said hook-lever.

The elevator carries a dash-pot 28, which passes over a fixed plunger 29 just before the 55 elevator reaches its lowest position, whereby the elevator is checked, but is allowed to settle slowly to its rest position. A dash-pot 30 is also provided for checking the downward movement of slide 10. This dash-pot is se- 60 cured to the lower end of bar 9, and the rod 31 of the dash-pot plunger passes through a loop 32 on the rear side of slide 10. There is a collar 33 on said plunger-rod above the loop, with which the loop engages as the slide goes

up, thereby withdrawing the plunger. There 65 is another collar, 34, on the plunger-rod below the loop, and between it and the loop is a leather buffer 35. When the slide 10 is released, it falls rapidly until the loop 32 thereon strikes the collar 34, or rather the buffer 70 35 resting thereon, whereupon its downward movement is checked and it is compelled to move slowly for the remainder of its downward movement.

The clutch 36, by which the lower sprocket 75 6 is attached to shaft 8, may be of any suitable construction—as, for example, a jaw-clutch, as shown. This clutch is moved to connect and disconnect the sprocket and shaft by the action of a bell-crank fork-lever 37, which 80 is connected by a link 38 with the armature-frame and a pair of alined electric magnets 40 41. This armature-frame is a rigid structure, of which the ends 42, to which the armatures 44 45 are attached, are rigidly connected by 85 rods 43. When, therefore, either magnet attracts its armature, the frame moves bodily. The circuits of these two magnets are normally incomplete, but means are provided for completing said circuits at the proper time to 90 throw the clutch in either direction. An electric generator 46 of any suitable construction may be connected by wire 47 with the metallic frame of the machine. A wire 48 from the other pole of the generator is connected with 95 an insulated contact-plate 49 in a switch-box 50, attached to the framework of the machine near the upper position of the elevator. (See Fig. 10.) There are two insulated contact- 100 plates 52 53 in said switch-box on opposite sides of the plate 49. A two-arm switch-lever 54 is secured to but insulated from a pivoted rocker 55, and the two arms of this switch are adapted to electrically connect the plate 49 with either of the plates 52 53, depending upon the position of said switch. The rocker is provided with a finger 56, which enters a notch in a slide-bar 58. A spring 59 moves this bar in one direction, and, in so moving, the bar moves the switch-lever 54 so 105 that it contacts with plates 49 and 52. This is the normal position of this switch. One side of the magnet 40 is connected by wire 60 with the plate 52, and therefore normally said magnet is connected with the generator. 110 The plate 53 is connected by wire 61 with one side of the other magnet, 41, which magnet is therefore not normally connected with the generator, but may be so connected by the movement of the switch-lever 54 to bring one 115 arm thereof in contact with plate 53. The other side of magnet 41 is always connected with the machine-frame by wire 62. The other wire, 67, of magnet 40 is connected with two insulated plates 63 64. In the machine 120 there are several rotating shafts which have other functions than those connected with the movement of the elevator. To one of these

shafts, as 65, a metallic arm 66 may be attached in such position that as the shaft rotates the arm will contact with the plate 63. This immediately completes the circuit of magnet 40, which magnet by attracting its armature throws the clutch so as to connect sprocket-wheel 6 with shaft 8. Immediately thereafter the elevator begins its upward movement, because it is attached to the sprocket-chain 5. Shaft 65, however, as it continues to rotate breaks contact with plate 63, and therefore if no other connection were provided between magnet 40 and the frame of the machine the clutch might not maintain the position into which it had been moved. Another connection is, however, provided by means of the insulated plate 64. Adjacent to this plate is a pivotedlever 71, made of metal, which is not insulated from the machine-frame. This switch-lever has an arm 72, which enters a notch in the armature-frame. When this armature-frame is moved up, as it is when the circuit of magnet 40 is first completed, this switch-lever 65 is moved into contact with plate 64, and thereby the circuit of magnet 40 is completed through another path. Now when the elevator has nearly reached its highest position an inclined flange 69 thereon engages in a notch 70 in the bar 58, thereby moving said bar in opposition to its spring, with the result of so moving the switch-lever 54 that its two arms will be brought into contact with the contact-plates 49 and 53, as shown in Fig. 10. This breaks the circuit of magnet 40 and completes the circuit of magnet 41, which magnet by moving the armature-frame down withdraws the clutch and disconnects sprocket-wheel 6 from shaft 8. When, therefore, the elevator is released by pawl 25, it is free to fall, the sprocket-wheel 6 running idly on shaft 8 while it is falling.

It will be understood that the precise connections shown by which the circuits of the magnets are completed and broken may be varied. It is desirable, however, that the elevator itself as it reaches its highest position shall cause the movement of an electrical switch or switches by which the circuit of one magnet is broken and the other magnet is completed and the sprocket-wheel 6 thereby disconnected from shaft 8.

Having described my invention, I claim—

1. In a machine for making type-bars, the combination of a vertically-movable elevator having a matrix-supporting rail, means for raising said elevator, a vertically-movable slide, a latch by which the elevator in its upward movement engages with and lifts said slide, means for withdrawing said latch, a spring-pawl for engaging with and sustaining the slide after the elevator has released it, means operated by the ascending elevator for withdrawing said pawl, a pawl for sustaining the elevator, means operated by the descend-

ing slide for withdrawing the last-mentioned 65 pawl, and means operated by the slide for removing the matrices from the elevator-rail.

2. In a machine for making type-bars, the combination of a vertically-movable elevator having a matrix-supporting rail, means for 70 raising said elevator, a vertically-movable slide, a latch by which the elevator in its upward movement engages with and lifts said slide, means for withdrawing said latch, a spring-pawl for engaging with and sustaining 75 the slide after the elevator has released it, means operated by the ascending elevator for withdrawing said pawl, a pawl for sustaining the elevator, means operated by the descending slide for withdrawing the last-mentioned 80 pawl, means operated by the slide for removing the matrices from the elevator-rail, and means operated by the elevator for severing the operative connection between the elevator and the mechanism for raising it. 85

3. In a machine for making type-bars, the combination of a vertically-movable elevator having a matrix-supporting rail, a vertically-movable rack-slide, an idle pinion with which said rack-slide engages, a horizontally-movable 90 rack-slide also engaging with said pinion and carrying a pressure-arm for engaging with the matrices on the elevator-rail, and moving them therefrom, mechanism for lifting the elevator, a latch by which the elevator in its 95 upward movement engages with and lifts the vertically-movable slide, and means for releasing said slide to the action of gravity.

4. In a machine for making type-bars, the combination of a vertically-movable elevator 100 having a matrix-supporting rail, a vertically-movable rack-slide, an idle pinion with which said rack-slide engages, a horizontally-movable 105 rack-slide also engaging with said pinion and carrying a pressure-arm for engaging with the matrices on the elevator-rail, mechanism for lifting the elevator, a latch by which the elevator in its upward movement engages with and lifts the vertically-movable slide, means for withdrawing said latch, means for 110 temporarily sustaining said vertically-movable slide after it has been released from the elevator, mechanism for releasing said slide to the action of gravity, and mechanism for sustaining the elevator temporarily and for 115 releasing it to the action of gravity.

5. In a machine for making type-bars, the combination of a vertically-movable elevator having a matrix-supporting rail, a vertically-movable 120 slide, a latch-lever pivoted to the elevator and adapted for engagement with said slide, and means whereby said latch-lever is withdrawn from its engagement with said slide and pushed out into the position for effecting such engagement. 125

6. In a machine for making type-bars, the combination of a vertically-movable elevator having a matrix-supporting rail, a vertically-

movable slide, a latch-lever pivoted to the elevator and adapted for engagement with said slide, a friction-roller carried by said lever, and cam-grooves for engaging with said roller 5 to move said latch-lever.

7. In a machine for making type-bars, the combination of an elevator having a matrix-supporting rail, a vertically-movable slide, a latch by which the elevator in its upward 10 movement engages with and lifts said slide, means for withdrawing said latch, a device which engages with said slide and temporarily supports it, and means whereby the elevator in its subsequent upward movement withdraws 15 said slide-supporting device.

8. In a machine for making type-bars, the combination of an elevator having a matrix-supporting rail, a vertically-movable slide, a latch by which the elevator in its upward 20 movement engages with and lifts said slide, means for withdrawing said latch, a spring-pawl which engages with said slide and temporarily supports it, a rock-shaft to which said pawl is secured, an arm secured to said 25 rock-shaft, and a projection on the elevator, which strikes said rock-shaft arm.

9. In a machine for making type-bars, the combination of a vertically-movable elevator having a matrix-supporting rail, means for 30 elevating it, a spring-pawl engaging with the elevator when in its most elevated position, and a vertically-movable slide carrying a cam adapted to engage with the tail of said spring-pawl to move it out of engagement with said 35 elevator.

10. In a machine for making type-bars, the combination of a vertically-movable elevator having a matrix-supporting rail, a vertically-movable rack-slide adapted to be engaged and 40 lifted by said elevator and to be released therefrom, mechanism operated by said slide for removing the matrices from the elevator-rail, and a fixed dash-pot adapted to check the downward movement of said slide.

45 11. In a machine for making type-bars, the combination of a vertically-movable elevator having a matrix-supporting rail, a vertically-movable rack-slide adapted to be engaged and lifted by said elevator and to be released therefrom, a mechanism operated by said slide for removing the matrices from the elevator-rail, a fixed dash-pot and a piston and rod for said 50 dash-pot, collars secured to said piston-rod, and a loop attached to the slide and embracing said piston-rod between said two collars.

55 12. In a machine for making type-bars, the combination of a vertically-movable elevator having a matrix-supporting rail, a latch-lever pivoted thereto, a vertically-movable slide,

and a spring-pawl carried thereby with its 6c lower end in the path of the said lever.

13. In a machine for making type-bars, the combination of a vertically-movable elevator, a sprocket-chain to which it is attached, and two freely-rotatable sprocket-wheels over 65 which said chain runs, with a clutch for connecting one of said sprocket-wheels with a rotating shaft, an electromagnet for closing said clutch, an electric switch adapted to be operated by the elevator in its upward movement 7c for breaking the circuit of said magnet, and means for opening said clutch.

14. In a machine for making type-bars, the combination of a vertically-movable elevator, a sprocket-chain to which the elevator is secured, two freely-rotatable sprockets over 75 which said chain runs, a rotating shaft, a clutch for connecting one of said sprockets to said shaft, a lever for operating said clutch, a pair of aligned magnets, an armature-frame to 8c which the armatures of said magnets are secured, a link connecting said armature-frame with the clutch-lever, means for closing the circuit of that magnet which closes the clutch, and an electric switch operated by the ascending elevator for breaking the circuit of that magnet and for closing the circuit of the other magnet, whereby the armature-frame is moved in the contrary direction to open the clutch. 85

15. In a machine for making type-bars, the combination of a vertically-movable elevator, a sprocket-chain to which the elevator is secured, two freely-rotatable sprockets over 9c which said chain runs, a rotating shaft, a clutch for connecting one of said sprockets to said 95 shaft, a lever for operating said clutch, a pair of aligned magnets, an armature-frame to which the armatures of said magnets are secured, a link connecting said armature-frame with the clutch-lever, a rotatable arm for 10 temporarily closing the circuit of that magnet which closes the clutch, an electrical switch operated by the armature-frame for closing said circuit through another path, a second electric switch for breaking the circuit of said 10c magnet and for closing the circuit of the other magnet, and means whereby the elevator in its upward movement moves said last-named switch in one direction, and in its downward movement moves the switch in the opposite direction. 11

In testimony whereof I hereunto affix my signature in the presence of two witnesses.
